UNITED STATES PATENT OFFICE.

DANIEL C. RIPLEY, OF PITTSBURG, PENNSYLVANIA, ASSIGNOR TO UNITED STATES GLASS COMPANY, OF PITTSBURG, PENNSYLVANIA, A CORPORATION OF PENNSYLVANIA.

DESIGN FOR A GLASS TILE.

No. 38,629.

Specification for Design.

Patented June 18, 1907.

Application filed April 2, 1907. Serial No. 366,048. Term of patent 14 years.

To all whom it may concern:

Be it known that I, DANIEL C. RIPLEY, of Pittsburg, in the county of Allegheny and State of Pennsylvania, have invented a new, original, and ornamental Design for Glass Tiles, reference being had to the accompanying drawing, forming part of this specification, in which

Figure 1 is a plan view of the glass tile, and Fig. 2 is an edge view thereof.

I claim:—
The ornamental design for glass tile, as shown.

DANIEL C. RIPLEY.
